US0D1052999S

(12) **United States Design Patent** (10) **Patent No.:** **US D1,052,999 S**
(45) **Date of Patent:** **** Dec. 3, 2024**

(54) **CASTER WHEEL FRAME**

(71) Applicant: **CHANG CHUAN ENTERPRISE CO., LTD.**, Changhua Hsien (TW)

(72) Inventor: **Yu-Hsiang Tso**, Changhua Hsien (TW)

(73) Assignee: **Chang Chuan Enterprise Co., Ltd.**, Changhua Hsien (TW)

(**) Term: **15 Years**

(21) Appl. No.: **29/871,318**

(22) Filed: **Feb. 16, 2023**

(51) LOC (14) Cl. **08-11**

(52) U.S. Cl.

USPC **D8/375**

(58) **Field of Classification Search**

(57) **CLAIM**

The ornamental design for a caster wheel frame as shown and described.

DESCRIPTION

FIG. 1 is a perspective view of a caster wheel frame showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in the figures are included for illustrating unclaimed portions of the caster wheel frame and form no part of the claimed design.

1 Claim, 7 Drawing Sheets
